UNITED STATES PATENT OFFICE.

KARL L. MAYERS AND MALCOLM A. NEWMAN, OF SAN ANTONIO, TEXAS.

ATTACHMENT FOR INTERNAL-COMBUSTION MOTORS.

Application filed October 21, 1922. Serial No. 596,127.

To all whom it may concern:

Be it known that we, KARL L. MAYERS and MALCOLM A. NEWMAN, citizens of the United States, residing at San Antonio, in the county of Bexar and State of Texas, have invented certain new and useful Improvements in Attachments for Internal-Combustion Motors, of which the following is a specification.

This invention relates to new and useful improvements in an attachment for internal combustion motors.

One object of the invention is to provide an apparatus of the character described whereby water and a lubricating oil will be mixed and vaporized and introduced into the mixing chamber of carburetter below the throttle valve thereof.

Another object of the invention is to provide an attachment of the character described whereby a lubricant in vaporized form may be mixed with the explosive mixture so as to form a component part thereof, said vaporized lubricant being deposited upon the valve seats and valves as well as the stems and bearings, thus forming an effective lubricant for these parts.

Another object of the invention is to provide an attachment of the character described whereby water converted into superheated steam and introduced into mixing chamber so as to form a component part of the explosive mixture thus increasing the force of the explosion, conducing to economy in the motive fluid and giving more power and life to the motor.

By passing oil through steam it produces an oily vapor which lubricates the valves and valve stems and produces an oil film for the valves to seat on insuring an air tight seat and prolonging the life of these moving parts.

It produces an oiling system identical to that of a steam engine, the most perfectly lubricated of all motors.

With the above and other objects in view the invention has particular relation to certain novel features of construction, operation and arrangement of parts, an example of which is given in this specification and illustrated in the accompanying drawings, wherein:—

Figure 1 shows a fragmentary side view, partially in section, of a motor vehicle with the attachment applied thereto.

Figure 2 shows a fragmentary front elevation of the attachment.

Figure 3 shows a fragmentary sectional view of the carburetter.

Figure 4 shows a fragmentary longitudinal sectional view of the exhaust manifold and the adjacent parts of the attachment.

Figure 5 shows a plan view of the tank and,

Figure 6 shows a front elevation thereof.

In the drawings, the numeral 1 designates a motor vehicle having the motor 2 equipped with the usual intake manifold 3 and exhaust manifold 4. The carburetter 5 is connected to the intake manifold in the usual way and the intake of the explosive mixture through it is controlled by the usual throttle valve 6. The numeral 7 designates a tank which is secured to the dash board of the vehicle underneath the hood. This tank is separated by the partition 8 into the chambers 9 and 10, the former of which contains water and the latter of which contains a lubricating oil, and these respective chambers having the glass gauges 11 and 12 to indicate the contents of each chamber. Leading from the bottom of the respective chambers are the lines 13 and 14 which enter the gauge casing 15 and are therein formed with the drip nozzles 16 and 17. The front of the gauge casing has a glass cover 18. The respective lines 13 and 14 have the check valves 19 and 20 and are also provided with respective needle valves 21 and 22. The gauge casing is carried by the cowl and the needle valves are hidden from view underneath the cowl but are within easy reach for manipulation so as to control the flow of fluid through the lines 13 and 14. Leading from the bottom of the gauge casing 15 there is a line 23 which is connected into the nipple 24. This nipple is threaded into the exhaust manifold 4 and anchored to it there is a thimble 25 which projects into said exhaust manifold and whose inner end is closed. The outer end of the nipple 24 has a gland 26 screwed therein which supports a tubular stem 27 which is arranged concentrically within said nipple and thimble and is spaced therefrom and whose lower end is open, the thimble 25 and stem 27, thus forming a trap to prevent the liquid mixture, hereinafter referred to, from reaching the carburetter. There is a discharge line 28

connected into the carburetter and is extended forming a perforated discharge nozzle 29 arranged below the throttle valve of the carburetter.

- 5 When the motor is running and the throttle valve 6 is open a partial vacuum will be created through the lines 28, 23 and 13, 14 respectively, and the water and oil will be forced out of the tank 7 through the lines
- 10 13 and 14 and will drip from the nozzles 16 and 17 into the casing 15 and will pass thence through the line 23 into the thimble 25 where the mixture is heated and vaporized by the exhaust gases and will pass in
- 15 vaporized form up through the stem 27 and thence through the line 28 and will be discharged through the nozzle 29 where it will be mingled with the motive fluid passing through the carburetter. The valves 21 and
- 20 22 are so adjusted that about three parts of water to one part of oil will be mixed together. These elements will drip from the nozzles 16 and 17 a drop at a time. They will be visible through the transparent cover
- 25 18 and the right proportions can be maintained by adjusting the needle valves 21 and 22. Oil will pass into the combustion chamber in vaporous form and will be deposited on the valve seats and valves as well as
- 30 on the valve stems and stem bearings thus lubricating these parts. The lubricant deposited on the valve seats will form a seal to prevent leakage past the valves when closed and will also form a cushion which
- 35 will minimize the wearing of the valves and seats. The water will enter the combustion chamber in vaporous form and the mixture

will greatly increase the efficiency of the motive fluid thereby reducing the amount thereof consumed.

It is to be noted that when the valve 6 is closed, or normally, when the motor is running idle the flow of the fluids from the tank 7 will be stopped so as to prevent the useless consumption of said fluids when they are not needed.

What we claim is:—

1. The combination with an internal combustion motor, of two liquid containers, a conduit leading from each container and uniting in a common conduit which enters the carburetor of the motor and is formed therein into a discharge nozzle, a section of said conduit being located in the exhaust manifold of the motor, said section being formed of an outside thimble closed at one end and an inside tubular stem, one end of which is spaced from the closed end of the thimble and is open.

2. The combination with an internal combustion motor, of two liquid containers, a conduit leading from each container and uniting in a common conduit which enters the carburetor of the motor and is formed therein into a discharge nozzle, a section of said conduit being located in the exhaust manifold of the motor, said section being formed of an outside thimble closed at its inner end, and an inside tubular stem spaced from the thimble and whose ends are open.

In testimony whereof we have signed our names to this specification.

KARL L. MAYERS.

MALCOLM A. NEWMAN.
